Geo. Kimmel. ATTORNEY.

Patented Feb. 19, 1929.

UNITED STATES PATENT OFFICE.

JAMES S. PATTERSON, OF ABILENE, TEXAS.

CAN OPENER.

Application filed March 15, 1927. Serial No. 175,519.

This invention relates to a tool designed for the opening of cans and the removal of bottle caps, but more particularly to a can opener and the invention has for its object to provide, in a manner as hereinafter set forth a tool whereby a can, can be readily and conveniently opened, by cutting into the top to partially or completely remove the same, and further with the tool including a cutting element which can be reversely operated.

A further object of the invention is to provide, in a manner as hereinafter set forth a tool of the class referred to including a runner carrying a cutting element and with the runner capable of being adjusted whereby the can top can be cut either in one direction or the other.

A further object of the invention is to provide, in a manner as hereinafter set forth, a tool for the purpose referred to wherein the runner carrying the cutting element, can be adjusted so that the runner can be utilized to remove caps from bottles in a convenient and expeditious manner.

A further object of the invention is to provide, in a manner as hereinafter set forth, a tool of the character referred to wherein the parts thereof are connected together to constitute a unit, being readily adjustable, one relative to the other, so as to permit the tool to be reversely operated when opening a can, or its utilization as a bottle opener.

Further objects of the invention are to provide, in a manner as hereinafter set forth a tool of the character referred to, which is simple in its construction and arrangement, strong, durable, compact, expeditiously performing its functions, thoroughly efficient in its use, conveniently operated, and inexpensive to manufacture.

With the foregoing and other objects in view, the invention consists of the novel construction, combination and arrangement of parts as will be hereinafter described in detail, illustrated in the accompanying drawing wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is an elevation of a tool, in accordance with this invention, showing the adaptation thereof in connection with a can

or receptacle for the opening thereof and with the can fragmentarily illustrated in dotted lines.

Figure 2 is a view similar to Figure 1 looking towards the tool in edge elevation.

Figure 3 is a fragmentary view in sectional plan and with the tool in position relative to the can top.

Figure 4 is a side elevation of the tool as applied to a bottle for the purpose of removing its cap.

A tool in accordance with this invention, which provides a can opener, as well as a bottle cap remover, comprises a runner element, 70 a cutter element and a handle element referred to generally by the reference characters 1, 2 and 3, respectively. The cutter element 2 is pivotally connected intermediate its ends to the runner element 1, approximately centrally thereof, as indicated at 4. The cutter element 2 is arranged against the outer side of the runner element 1.

The runner element 1 includes an intermediate portion 5 and a pair of horizontally-disposed end portions 6, 7 extending at opposite inclinations and which are angularly disposed with respect to the intermediate portion 5 and extend outwardly therefrom. The end portion 6 is of L-shaped contour and is formed with a pair of arms 8, 9, the latter being disposed substantially at right angles with respect to the former and which opposes and is spaced from the outer face of the intermediate portion 5 by the arm 8. At the point of joinder 90 of the arm 8 with the intermediate portion 5 the said arm is formed with a pair of oppositely extending notches 10, 11 providing seats for the rim 12 of the can 13 and the top of the latter is indicated at 14. The free end or rather outer end edge of the arm 9 is formed with an arcuate depression 15. The end portion 7 is of T-shaped contour to provide at its outer end a pair of oppositely extending lugs 16, 17 forming abutments to engage the outer face of the rim 12 of the can 13. The intermediate portion 5 is of acute contour and is formed with an opening 18 for the passage of the pivot 4.

The cutter element includes a tapered shank 19 which merges at its inner end in a segment shaped cutter member 20 formed with a tapered free end 21. The cutter member 20 at a point between its transverse median and its point of joinder with the shank 19 is formed with an opening 22 for the passage of the pivot 4. The curvature of the

cutter member 20 conforms to the curvature of the intermediate portion 5 of the runner element whereby the former can be swung to the position shown in Figure 4 to be arranged in abutting engagement with respect to the outer face of the intermediate portion 5 of the runner element. The marginal portion at each side of the cutter member 20, from a point aligning with the opening 22 formed therein to the free end of said member is bevelled, as at 23, to provide a pair of cutting edges 24 which merge into each other at the pointed end 21 at a point arranged at the longitudinal median of said cutter member.

15 The shank 19 of the cutter element, is fixedly secured to the handle element 3 and the latter, preferably, is of cylindrical cross section and of the desired length.

20 The cutter element 2 is in the form of a lever and can be oscillated on the pivot 4 to perform its cutting function. The notches in the end portion 3 and the setting up of the end portion 7 of T-shaped contour permits of adjusting the runner element 1 upon the 25 rim 12 of the can, and the notches as well as the T-shaped end portion provide guides for the runner when the same is shifted upon the rim 12 of the can during the cutting operation to partly or completely remove the can top. The construction of the runner element 30 1 permits of the tool to be operated either one direction or the other, and couples the tool to the can.

35 The tool is equally adaptable as a bottle cap remover and for such purpose when the tool is in the position as shown in Figure 4, the arm 9 can be positioned under the cap 25 and the cutter member 20 positioned on top of the cap, then on a lowering movement of the handle element 3, the cap 25 will be removed from the bottle neck 26 through the action of the arm 9 against the edge of the cap. The curved depression or concavity 45 15, at the free end edge of the arm 9 permits the latter to snugly abut against the neck 26 as the curve of the depression conforms to the curvature of the neck.

50 In the use of the tool the pointed end 21 of the cutter member 20 is pierced through the top of the can as shown in Figure 2, and the runner element 1 superimposed upon the rim 12 of the can and with said rim seated in one of the notches of the end portion 6

and with one of the lugs 16 or 17 abutting against the outer face of the rim 12. Then 55 by oscillating the cutter element 2 the can top will be severed partly or completely from the body of the can as will be readily apparent.

It is thought the many advantages of a 60 tool, in accordance with this invention and for the purpose set forth can be readily understood, and although the preferred embodiment of the invention is as illustrated and described, yet it is to be understood that 65 changes in the details of construction can be had which will fall within the scope of the invention as claimed.

What is claimed is:—

1. A tool for the purpose set forth comprising a runner element formed of an arcuate intermediate portion terminating at one end in an angularly disposed horizontally extending, oppositely projecting T-shaped end portion for overlapping the can rim and at its other end in an angularly disposed horizontally extending L-shaped end portion having one of its arms provided with oppositely extending transversely disposed notches for overlapping the can rim, said end portions extending at opposite inclinations with respect to each other, and a cutter element pivotally supported from said intermediate portion and including a cutter member conforming in curvature to the curvature of said intermediate portion.

2. A tool for the purpose set forth comprising a runner element including a body portion provided at one end with a laterally extending angularly disposed, notched, combined guide and coupling means for receiving and overlapping a can rim, said means projecting outwardly from said body portion, said element further including a laterally extending angularly disposed, combined guide and abutment means projecting outwardly from the other end of said body portion for seating on and abutting the outer face of the can rim, and a cutter element pivoted intermediate its ends against the outer face of said body portion intermediate the ends of the latter.

In testimony whereof, I affix my signature hereto.

JAMES S. PATTERSON.
